UNITED STATES PATENT OFFICE.

CHARLES G. PERKINS, OF HARTFORD, CONNECTICUT.

LAMP-SHADE HOLDER.

SPECIFICATION forming part of Letters Patent No. 411,107, dated September 17, 1889.

Application filed December 23, 1887. Serial No. 258,823. (No model.)

To all whom it may concern:

Be it known that I, CHARLES G. PERKINS, a citizen of the United States, residing at Hartford, in the county of Hartford and State 5 of Connecticut, have invented certain new and useful Improvements in Shade-Holders for Electric and other Lamps, of which the following is a specification.

My invention is especially adapted to use 10 with electric incandescent lamps; but it may be applied to other lamps when convenient. It is well known that shades for electric and other lamps are not commonly made in a mold, but are shaped as nearly as possible to 15 the same dimensions without molding. The result of this is that scarcely any two shades are of exactly the same size at the rim, where they are usually attached to the shade-holder.

The object of the present invention is to 20 make an adjustable shade-holder, so that within certain limits it can be adjusted to fit shades of different sizes.

I have illustrated my invention in the accompanying drawings, in which—

25 Figure 1 is an elevation of an incandescent lamp socket and shade with my shade-holder attached. Fig. 2 is a perspective view of my shade-holder detached from the lamp. Fig. 3 is a plan showing a modification of my invention.

30 Referring to the drawings by letter, A is an ordinary incandescent electric lamp, and B is the lamp-socket. C is the lamp-shade, and D is my shade-holder for supporting it. The 35 parts A, B, and C are of the usual kind and form no part of the present invention. I have simply adapted the lamp-socket B to use with my present shade-holder by forming a groove b around it.

40 For connecting my shade-holder with the lamp-socket I provide a spring-ring E, which is open at e and provided with lugs f, through which a screw passes for closing the ring more or less tightly around the socket. From this 45 ring extend arms G G to make connection with a larger open ring H. Two of the arms G' G' are arranged on opposite sides of the opening in the ring H, and are fluted, corrugated, or notched, as shown, for a purpose that 50 will be presently described. Upon the two

arms last referred to a slide I is adapted to move.

The operation of adjusting the holder to a shade is accomplished by moving the slide I to its highest position and then inserting the 55 rim of the shade in the ring H, which has sprung open to receive it. Then by shaking the slide downward or moving it down with the fingers, or by simply pressing the lower ring together with the fingers, the slide will 60 be moved down and holds the ring tightly around the shade. Ordinarily it will be sufficient to close the ring around the shade and the slide will fall down of itself. If this should not be the case, it will move down 65 upon being touched with the fingers. Owing to the corrugations in the arms G' G' the slide is held in place and also holds the ring in place under the rim of the shade.

It will be seen that my shade-holder is 70 adapted to be fitted to any shade within certain limits. The limits can be increased at will by widening the opening in the ring H and lengthening the slide, or, better, by changing the angle of the two corrugated arms. 75

The drawings show the opening in both rings located between the fluted arms. It is obvious, however, that it is only necessary that the opening in the ring which the arms control should be so located. 80

It will be seen that one of the advantages of this holder is the facility with which it can be adjusted to a shade.

While I have only described, specifically, the shade-holding ring as being open in one 85 place, I do not confine myself to that construction.

In Fig. 3 I have shown the lower ring in two sections—that is, open in two places—and the fluted arms placed at both openings in 90 order to control both. By this construction I produce a holder which is adapted to fit a greater variety of sizes of shades. In ordinary use one of these openings may be kept locked at one position and the other used in 95 adjustment to the shade. This is optional, however.

I claim as my invention—

1. The combination, with a shade-holder for lamps, of a spring-ring for grasping the lamp, 100

a spring-ring for grasping the shade, two fluted or corrugated arms connecting the two rings and located one on each side of the opening in the shade-ring, and a sliding catch, as and 5 for the purpose described.

2. The combination, in a shade-holder for lamps, of two open spring-rings, one adapted to connect with the lamp and the other with the shade, secured together by a plurality of 10 arms or braces, two of which are corrugated, fluted, or notched, and are located on opposite sides of the opening in the ring which supports the shade, the said fluted, corrugated, or notched arms being embraced by a 15 sliding catch, which is adapted to hold the shade-ring closed against its own spring force.

3. The combination, in a shade-holder for lamps, with a spring-ring for grasping the lamp and a spring-ring for grasping the shade, of pairs of fluted arms connecting the two 20 rings, the individuals of each pair being located, respectively, on the opposite sides of the openings between the sections of the shade-ring, and adjustable links for holding the individuals of each pair together, as set forth. 25

In testimony whereof I affix my signature in presence of two witnesses.

CHARLES G. PERKINS.
